Harry W. Bowen.
ATTORNEY.

UNITED STATES PATENT OFFICE

WILLIAM H. HEFFERNAN, OF NORTH ADAMS, MASSACHUSETTS, ASSIGNOR TO HEFFERNAN BRUSH COMPANY, INC., OF NORTH ADAMS, MASSACHUSETTS, A CORPORATION OF MASSACHUSETTS

COMBER ROLL FOR COMBING RAW COTTON

Application filed May 10, 1930. Serial No. 451,328.

This invention relates to improvements in comber rolls for combing raw cotton.

An object of the invention is to provide means for attaching these rolls to the driving shaft. At the present time, difficulty is experienced in securing the shaft to the roll since the rolls which are made of layers of paper do not furnish sufficient strength for securing a shaft thereto. Broadly, the invention comprises a paper tube which is formed with two semi-circular cylindrical portions, the ends of which are reduced in diameter and formed with radial kerfs in the reduced part. Semi-circular cap pieces are fitted onto the reduced portions. These cap pieces are formed with ribs which enter the kerfs or grooves. A collar is located or placed outside of the two semi-cylindrical cap pieces or members. The collar is formed with threaded openings for receiving set screws that are forced against the semi-circular members, thus moving them tightly or firmly against the reduced ends of the semi-circular cylindrical members, whereby these members are firmly clamped together and to the collar.

As a modification, the cylindrical members are formed with openings for receiving pins that enter openings in a bearing member which bearing member closely fits the opening in the tube. The ends of the bearing member are reduced in diameter for seating in the bearing blocks of the machine, as will be described.

Referring to the drawings:—

Fig. 1 is a perspective view of the two halves of the cylindrical member and showing the cap pieces and clamping collar in place.

Fig. 2 is a detail sectional view showing the manner of securing the bristles to the layers of paper composing the cylindrical member.

Fig. 3 is a perspective view of the cylindrical member illustrating one of the reduced ends and the radial kerfs therein.

Fig. 4 is a separated view of the cap pieces which engage the reduced ends of the paper cylinder.

Fig. 5 is a perspective view of the clamp-

ing collar which engages the cap pieces, and

Fig. 6 is a modification showing the pin means for securing the bearings to the layers of paper comprising the paper tube.

Referring to the drawings in detail:

1 and 2 designate the two semi-cylindrical members, composed of paper which form the cylindrical tubular member, the layers of which are indicated at 3. The ends of the cylinder, only one of which is shown, are reduced in diameter, as indicated by the numeral 4. 5 and 6 indicate radial kerfs or grooves that are cut in the reduced ends of the semi-cylindrical members. These kerfs are located opposite each other. 7 and 8 designate two cap pieces that are placed on the reduced portion 4 with the ribs 9 and 10 which enter the kerfs 5 and 6. The inner surfaces 11 and 12 rest upon the reduced surface 4 and the annular end surfaces 13 and 14 engage the ends 15 and 16 of the semi-cylindrical members 1 and 2. For the purpose of clamping the members 7 and 8, the ring or collar 17 is provided as shown in Fig. 5 having the set screws 18 and 19 which engage the outer surface of the members 7 and 8 and force the same firmly against the two halves of the semi-cylindrical members, whereby the same are firmly secured on the paper roll. The ribs 9 and 10 which engage the kerfs 5 and 6 serve to drive the roll; it being understood that a shaft passes thru the opening 20 of the cylinder, and the registering openings of the clamping members 7 and 8 and the opening 22 of the clamping collar or ring.

It will, therefore, be seen that there is no danger of the clamping means working loose on the cylinder, when the shaft, not shown, is operated.

Referring to Fig. 2, the bristles 23 are secured to the layers of paper 3 by means of the staples 24 which are located in openings 25. This is the usual manner for attaching the tuft of bristles to a roller.

Referring to Fig. 6 which illustrates a modification of the means of attaching the bearing members to the cylindrical paper roll, 26 are pins which thru openings 27 in the ends of the paper tubular member which

is not made in two pieces, as shown in Figs. 1 and 3. These pins enter registering openings 28 in the bearing member 29. The reduced portion 30 is the part that rests in the usual bearing boxes, not shown. The roll shown in Fig. 6 may be employed for conveying the dyes from a suitable vat to a compression or printing roll, not shown. These rolls are composed of paper and treated with boiled sulphur to render them impervious to the dyes and for retaining their true cylindrical shape which is not true of wooden cylinders.

What I claim is:

- 15 1. In a comber roll device of the kind described, a cylindrical member formed with an opening therethrough, said member being divided into a plurality of sections, means for securing the members together, said means comprising sectional cap pieces for engaging the ends of the cylinder, co-operating elements between the cylinder and the caps, and means for forcing the cap members to the cylinder.
- 20 2. In a comber roll device of the kind described, a cylindrical member formed with an opening therethrough, said member being divided into a plurality of sections, means for securing the members together, said means comprising sectional cap pieces for engaging the ends of the cylinder, co-operating elements between the cylinder and the caps, and means for forcing the cap members to the cylinder, said means comprising a collar provided with set screws which engage the sections of the cap.
- 25 3. In a comber roll device for the purpose described, a cylindrical member formed with a reduced end portion and kerfs in the ends of the reduced portion, caps formed with projections for entering the kerfs, and a collar or ring engaging the cap members, and means on the collar for forcing the caps firmly against the cylinder and the ribs into the kerfs.
- 40 4. A comber roll device for the purpose described comprising a cylindrical member composed of laminations, means for attaching a driving element to the cylindrical member comprising a sectional collar formed with projections and the cylinder having kerfs to receive the projections, a ring engaging the sectional collar, and means on the ring for forcing the members of the sectional collar toward each other for clamping the said section to the cylinder.
- 45 5. As an article of manufacture a comber roll for combing raw cotton comprising, a tubular member, composed of layers of paper, a bearing member, and means for securing the bearing member to the tubular member.

In testimony whereof, I hereunto sign my name this 12th day of April, 1930.

65 WILLIAM H. HEFFERNAN.
